Primary Examiner — Cynthia M Chin(74) *Attorney, Agent, or Firm* — McDermott Will & Emery LLP(57) **CLAIM**

I claim the ornamental design for a ride-on vehicle, as shown and described.

DESCRIPTION

FIG. 1 is a perspective view of a ride-on vehicle according to the new design;

FIG. 2 is a side view of the ride-on vehicle shown in FIG. 1; FIG. 3 is a top view of the ride-on vehicle shown in FIG. 1; FIG. 4 is a front view of the ride-on vehicle shown in FIG. 1; FIG. 5 is a back view of the ride-on vehicle shown in FIG. 1; and,

FIG. 6 is a bottom view of the ride-on vehicle shown in FIG. 1.

Features shown in broken lines in the drawings are not part of the claim.

1 Claim, 5 Drawing Sheets(56)
